ELECTRIC SABER SAW

Carl E. Weller and Donald R. Fegley, Easton, Pa., and
Alden J. Brassaw, Phillipsburg, N.J., assignors to Weller
Tool Corporation, Luquillo, Puerto Rico, a corporation
of Puerto Rico

Filed Feb. 1, 1963, Ser. No. 73,406

Term of patent 14 years

(Cl. D93—3)

Fig. 1.

Fig. 2.

*Fig. 3.**Fig. 4.**Fig. 5.*FIGURE 1 is a perspective view of an electric saber saw embodying our new design, as seen from one side thereof;

FIGURE 2 is a side elevation view thereof as viewed from the opposite side;

FIGURE 3 is a top plan view thereof;

FIGURE 4 is an end elevation thereof as viewed from the left-hand end of FIGURE 2; and

FIGURE 5 is an end elevation thereof viewed from the right-hand end of FIGURE 2.

We claim:

The ornamental design for an electric saber saw, substantially as shown.
